UNITED STATES PATENT OFFICE.

JOSHUA GEORGE WAGSTAFF, OF DUKINFIELD, ENGLAND.

SECTIONAL BOILER.

SPECIFICATION forming part of Letters Patent No. 733,688, dated July 14, 1903.

Application filed June 17, 1902. Serial No. 112,110. (No model.)

To all whom it may concern:

Be it known that I, JOSHUA GEORGE WAGSTAFF, heating and ventilating engineer, a subject of the King of Great Britain and Ireland, 5 of The Alma Iron Works, Dukinfield, in the county of Chester, England, have invented certain new and useful Improvements in Sectional Boilers for Heating Water or Generating Steam, (for which I have made an application for patent in Great Britain, No. 23,594, dated November 21, 1901,) of which the following is a specification.

My invention relates to sectional boilers used for heating water for radiators or other 15 purposes or for generating steam, as is well understood.

The object of my invention is to construct the sections of such a boiler so as to offer very large area of heating-surface in the fire- 20 box and flues, free circulation for the hot gases in a transverse and vertical direction, and of such a shape that the gases will ascend in intimate contact with the whole, or practically the whole, surface of the sections.

25 The accompanying drawings clearly illustrate my invention.

Figure 1 is a front elevation of one of the sections of the boiler. Fig. 2 is an end view looking in the direction of the arrow marked 30 J, Fig. 1. Fig. 3 is a sectional elevation of the section. Fig. 4 is an end view from the end marked R, Fig. 3. Fig. 5 shows on the left hand a half-front elevation of the boiler, and on the right hand a half-section through 35 the line K L, Fig. 7. Fig. 6 is a sectional side elevation, the portion marked with the bracket M being taken through the line G H and the part marked with the bracket M' through the line G' H', Fig. 1, and the part 40 marked N being taken through the line A B, Fig. 1. Fig. 7 is a plan view, partly in section, showing the various sections of the boiler assembled together, the back portion a, one 45 of the intermediate sections b, and the front section c being shown in a section taken through the line C D, Figs. 1 and 5, another intermediate section e being shown in section on the line E F, Fig. 1.

Each tubular section is cast in two separate 50 identical halves, and each half consists of an outer vertical tube f and head g branching inward, which carries an upper chamber,

as clearly shown in Figs. 1 to 4. The bottom of this upper chamber is formed with a portion or swell h, projecting at the side a little beyond the inner edge of the upper chamber. This projection h is formed to extend about half-way across the width of the upper chamber, as shown in Fig. 1. The upper chamber is further subdivided above the projection h by means of a narrow slit or aperture i, which divides the upper chamber into two short vertical tubes j k and serves to permit the insertion of an angle or cranked cleaning-brush. When the sections are placed in position and bolted together by bolts l, (see Figs. 5 and 7,) the halves of each section are arranged right and left hand, and a number of side vertical tubes f are thus obtained, the heads g of the vertical tubes and upper chambers projecting inward, and forming a roof for the fire and smoke chamber. The ends of the bottom projections h, formed on the upper chambers, are placed together and provide a central vertical passage m between the inwardly arranged upper chambers, leading to a suitable smoke box and flue n, formed at the top of the series of sections. The sections are connected together by suitable joints o at the two outer corners and at the bottom p of the vertical tubes, thus forming four joints for each complete section. By connecting the sections at the top corners instead of centrally, as usual, the construction will allow of numbers of outlet connections being taken therefrom at a much lower level than if the connection was at the center. To form a gas-tight joint, the outer edges of the sections are provided with a web q, so that when the webs of adjoining sections are brought together a perfect joint can be easily attained by the use of cement or the like, which will be more clearly seen from an inspection of Fig. 7. Such being the general construction and arrangement of the tubular sections I will now describe the shape in cross-section of such tubes, whereby I am enabled to subject practically the entire area of such tubes to the action of the fire and ascending gases.

The vertical tubes f I form of triangular shape in cross-section, the base of the triangle being at the extreme outer edges of the sections at the point of junction with the ad-

joining sections, the apex of the triangle being arranged inward. Instead of inducing a draft horizontally throughout my improved water-heater I arrange for the flames and gases from the fire to ascend vertically. At each side of the fire, therefore, the rows of triangular-shaped tubes form a series of triangular recesses or shafts *r*, (shown clearly in the plan view, Fig. 7,) up which the gases are introduced, so that the entire area of the vertical tubes *f* is in intimate contact with the hot gases. The heads *g* of the vertical tubes are formed in the shape of a triangle with the apex downward, (see Fig. 6,) so that the ascending gases meet the apex and pass upward at each side of and in contact with the entire area of the horizontal heads of the vertical tubes. The gases are deflected by the bottom projections *h* to enter the upper chambers of the sections toward the sides thereof, afterward being drawn to the center by the central flue, as indicated by the arrows in Fig. 5. The two vertical tubes *j k* forming the upper chamber are also triangular in cross-section, (see Fig. 7,) each one being arranged with apex toward the dividing-slit. The ascending gases are deflected by the bottom projections *h* of the upper chamber and pass to the smoke chamber and flue, the upper short tubes offering their entire surface to the contact of the gases. I thus obtain a large contact-surface and free circulation of the gases, also vertical circulation of water throughout the system. There is no liability to breakage by contraction, and in addition to economy in point of construction there is freedom for expansion and contraction of the various sections when assembled.

Although I have instanced triangular tubes in cross-section, it will be understood that

that shape may be varied, as the tubes may be rectangular, square, or round ended. In the case of a steam-generator the tubes of the upper chamber might be formed square, as shown in cross-section at *O*, Fig. 6, so as to increase the heating-surface and fluid-space.

The various sections when assembled are provided with a suitable fire-grate, and front and back water sections *c a* with fire-doors, flue-doors, water inlets and outlets, and the like, and stand *t* to complete the boiler, although as these form no part of my invention it is unnecessary to enter into details thereof.

I declare that what I claim is—

A sectional boiler having a transverse and vertical draft for heating water or generating steam, formed in sections made in identical halves each separate section comprising a vertical tube, recesses or shafts between the vertical tubes, a head branching inward, a deflecting-rib at the upper part of the head and an upper chamber divided into two vertical tubes, the tubes of the sections being formed at their outer edges with a web to effect the junction of the sections, a fire-grate, a smoke box and flue formed at the top of the series of sections, a front water-section having a fire-door and flue-doors, a back water-section and stand the sections being in communication with each other at the top outer corners and the bottom corners, the sections of the boiler being placed back to back, substantially as described.

In witness whereof I have hereunto set my hand in presence of two witnesses.

JOSHUA GEORGE WAGSTAFF.
